UNITED STATES PATENT OFFICE.

JOSEPH J. STOCKER, OF ST. LOUIS, MISSOURI.

BLOWER.

996,160.

Specification of Letters Patent. Patented June 27, 1911.

Application filed September 21, 1910. Serial No. 583,046.

To all whom it may concern:

Be it known that I, JOSEPH J. STOCKER, a citizen of the United States, and resident of St. Louis, Missouri, have invented certain 5 new and useful Improvements in Blowers, of which the following is a specification.

This invention relates to improvements in blowers and has for its object a casing in which is mounted a revolving member, the 10 casing being so constructed as to receive and carry all of the air from the bottom of the revolving member, the upper portion of the casing so arranged as to permit the revolving member to operate freely and ineffectively.

A further object of my invention is to provide a revolving member arranged to operate on a stationary shaft, a shield mounted rigidly on the shaft inclosing the upper, inner 20 portion of the revolving member, its one end being pointed so as to eliminate the greater portion of the humming caused by the rapid revolution of the revolving member, and a lower casing so constructed as to receive the 25 air, and an additional spout for taking care of the air which is carried past and not admitted into the lower receptacle proper.

This invention is an improvement over applicant's patent issued to him July 12, 30 1910, No. 963,957 for blowers and the most essential feature of the improvement lies in a construction of casing and pointed inner shield to eliminate the greater portion of the noise created by applicant's former invention, and to gather and utilize all of the air pressure created by the revolving member.

Figure 1 is a side elevation of my complete invention. Fig. 2 is a vertical, sectional view of the same taken on the line 40 2-2 of Fig. 3. Fig. 3 is an end view of the same. Fig. 4 is a cross sectional view taken on the line 4-4 of Fig. 5, and viewing the same in the direction indicated by the arrow. Fig. 5 is a top plan view. Fig. 6 is a detail 45 perspective view of the butting end of the auxiliary spout made use of in gathering and conveying to the delivery end of the machine that portion of the air which fails to enter the air chamber proper. Fig. 7 is a 50 detail perspective view of the shield made

use of inclosing the upper inner portion of the revolving member, and for eliminating the greater portion of the humming created by the revolving member.

In the construction of my invention I provide a suitable base plate 8 on which is mounted a casing 9 so constructed as to act as an air chamber for the reception of the compressed agitated air caused by the rapid revolution of the revolving member 10. On 55 the base plate, and on each side of the casing are rigidly supported supports or standards 11, which are provided with supporting heads 12 in which is supported and rigidly retained in position a tubular shaft 13, the 60 same being provided with openings 14, which communicate with like openings 15 formed in the caps of the supports and through which oil is admitted into the hollow shaft. On this shaft is mounted the 65 revolving member 10, which consists of a pair of rings 16, each having integral arms or spokes 17 terminating at the center in a hub 18, said hubs provided with sleeves which snugly fit over the tubular shaft, and 70 on said sleeves are rigidly mounted pulleys, 75 by which the revolving member is rotated.

The tubular shaft 13 is provided at its bottom with small apertures which communicate with the hubs and sleeves and are 80 for the purpose to permit the oil which is inserted into said shaft to continuously lubricate that portion of the revolving member which operates on the shaft. This construction is clearly shown in Fig. 4 of the drawings.

In the space between both of the rings 16 and at suitable intervals apart are firmly riveted, or otherwise secured, a plurality of curved agitator blades 19, the relative position of said blades being clearly shown in 90 Fig. 2. The agitator blades or paddles, as arranged between the two rings are of two sizes and are arranged alternatively, one long and one short. The object of the short paddles located between two of the long ones is to divide the outlet space between the same and assist in gaining a greater agitation to 95 the air. The connection of the spoke 17 to the rings 16 is such as to provide an offset or 100

recess 20 to permit the insertion of the shield 21. This shield consists of a rim 22 supported on spokes 23 terminating into the hub 24 and by means of this hub the shield 5 is rigidly supported on the tubular shaft 13 within the revolving member and between each of its hubs 18. The forward end of the shield 22 is suitably tapered forming an arrow head 25, this tapered end being one of 10 the essential features of my improvement, that by this formation the greater portion of the humming caused by the rapid movement of the revolving member is eliminated.

Connected to the casing 9 and located 15 over the upper portion of the revolving member is a hood 26 consisting of a flat sheet of metal 27 held rigid by the stiffening ribs 28.

On the discharge end 29 of the casing 9 is 20 attached the delivery spout 30 through which the agitated air is conveyed to its desired destination. On the top of the discharge end 29 and immediately in front of the revolving member is located a casting 25 31 which acts as the butting end of the auxiliary spout 31 by which said spout is firmly secured, the discharge end 33 of the auxiliary spout communicating with an opening 34 formed in the upper end of the spout 30. It will be observed that the auxiliary spout 32 is of curved construction and that its passage-way is tapered in form, the greatest end being its inlet, and located immediately in front of the revolving member, and its purpose is to catch and convey 35 that portion of the air agitated by the paddles or agitators, between the point 35 of the casing 9, and the point 36 of the auxiliary spout. It has been discovered by continuous 40 experiment that a certain amount of agitated air is lost by striking the solid wall of the housing between these two points.

The space between the shield 22 and the 45 hood 27 is what applicant terms a dead passage. The paddles or agitators while traveling through this space are performing no function as no air is admitted into this space. The only operative portion of the revolving member is that extending into the casing 9 50 and in front of the auxiliary spout 32. The air is admitted through the center and the centrifugal force of the revolving member has a tendency to throw off the air on a direct line from the paddles or agitators into 55 the air chamber of the casing 9.

The rear portion of the casing 9 as indicated by the numeral 37 is of greater depth than the remaining portion of said casing and acts as a pocket for the free reception 60 of the agitated air, the volume of air in said pocket forming a cushion preventing a back pressure of said air into the revolving member.

Having thus fully described my invention, 65 what I claim as new and desire to have se-

cured to me by the grant of Letters Patent, is:

1. A blower of the class described comprising a revolving member, a casing mounted below the revolving member, a shield 70 having one end tapered located rigidly within the revolving member and an auxiliary spout leading from the periphery of the revolving member to the outlet of the casing, substantially as specified. 75

2. A blower comprising a casing acting as an air chamber, a stationary shaft, a revolving member mounted on said shaft above the casing, a hood mounted over the revolving member and supported to the casing, a 80 shield rigidly mounted on the stationary shaft inclosing a portion of the inner surface of the revolving member, said shield having one end tapered and pointed to eliminate the greater portion of the humming 85 caused by the revolution of the revolving member, an auxiliary spout located in front of the revolving member and communicating with the discharge end of the casing, substantially as specified. 90

3. A blower comprising a revolving member composed of a pair of rings, agitator blades located between said rings, said revolving member rotatably mounted, a stationary shaft on which said revolving member is supported, a casing acting as an air chamber located beneath the revolving member, a shield rigidly mounted on said stationary shaft, one end of said shield being tapered and pointed to eliminate the greater 100 portion of the humming usually created by the rapid revolution of the revolving member, an auxiliary spout located above the casing, its inlet end located in front of the revolving member and its discharge end 105 communicating with the outlet of the casing, substantially as specified. 110

4. A blower of the class described comprising a revolving member, a casing over which the revolving member is mounted, a 110 stationary shield located centrally in the revolving member closing the upper inner surface thereof, the forward end of said shield being tapered and pointed so as to eliminate the greater portion of the humming caused 115 by the revolution of the revolving member, and an auxiliary spout located in advance of the revolving member to catch and convey that portion of the agitated air which failed to enter into the air chamber of the 120 casing, substantially as specified.

5. A blower comprising a revolving member revolvably mounted on a stationary tubular shaft, a casing acting as an air chamber located beneath the revolving member, a 125 hood located around a portion of the inner periphery of the revolving member inclosing the upper portion thereof, a shield rigidly mounted on the shaft inclosing the upper inner surface of the revolving member, 130

the forward end of said shield being tapered or pointed, an auxiliary spout located on the casing and located in advance of the revolving member to catch and convey the air which failed to enter the air chamber and to convey the same to the discharge end of the casing, substantially as specified.

In testimony whereof, I have signed my name to this specification, in presence of two subscribing witnesses.

JOSEPH J. STOCKER.
